TAPE REWINDING DEVICE AND METHOD

Mark B. Andrews, Kirkwood, Mo.

Application October 24, 1945, Serial No. 624,153

3 Claims. (Cl. 242—75)

1

The present invention relates to a tape rewinding device. More particularly, it relates to a device that is peculiarly adapted for rewinding pressure-sensitive tape.

It is an object of the invention to provide a rewinding machine that may be used with pressure-sensitive tape, and which will rewind the same without telescoping of the rewound roll.

A further object of the invention is to provide a rewinding device of this kind that operates through a slip friction, particularly one having an adjustable tension.

A further object of the invention is to provide a tape rewinding device wherein the tension for unwinding the tape from a former roll is applied to a peeling drum, other than that upon which the tape is rewound, with a friction drive between the peeling drum and the rewinding roll.

A further object of the invention is to provide a rewinding device with means for adapting it to use with laminated tape.

A further object of the invention is to provide a peeling roll or drum which has only limited surface engagement with the tape. Another object is to provide a rewinding device which can readily meter the amount of tape rewound in terms of revolutions of the driving drum.

In the drawings:

Fig. 1 is a front elevation of the rewinding machine;

Fig. 2 is an end elevation, partly broken away;

Fig. 3 is a rear elevation of one side of the machine;

Fig. 4 is a section on the line 4—4 of Fig. 2, taken through the peeling drum mounting; and

Fig. 5 is a section on the line 5—5 of Fig. 2, showing the rewinding drum and the friction clutch.

The rewinding machine may conveniently be mounted on a base 10 having a horizontal portion 11 and a vertical portion 12.

A tape supply core 13, in the form of a ring, is shown as mounted upon a spindle 14 that extends from one face of the vertical support 12.

The core 13 has tape 17 coiled thereon. This tape may be the pressure-sensitive type of tape, formed from cellophane or the like, with a suitable adhesive on one side. This tape may be wound through a processing mechanism 20, which may be a printing mechanism or other suitable processing means. It is frequently desired to print legends upon the tape. Other processing known in the art is stripping or slitting means, which may divide the tape into several narrower strips.

2

From the means 20, the tape 17 is drawn under an idler roll 21. Thence it goes over a peeling drum, generally indicated at 22, and finally is drawn down onto a rewind core 23, which is mounted upon a rewind shaft 24, to be explained in more detail hereafter. It is understood that the idler roll 21, the peeling drum 22 and the shaft 24 are all mounted in the vertical support 12.

Where it is desired to produce a laminated tape, an additional roll 25 of tape may be supported upon a shaft 26, also mounted upon the support 12.

The roll 25 illustrates the type of tape supporting roll preferred in this mechanism. As shown in Fig. 2, the shaft 26 is threaded into the support 12, for adjustment lengthwise, and is secured in adjusted position by a wing nut 27 behind the support.

The shaft 26 has a fixed flange 28 at the front of the panel. An adapter disc 29 is slipped over the shaft 26 against the flange 28. An annular core 30 of the tape roll 25 is fitted over the shaft, and engages over a circular projection 31 on the disc 29. Then a similar disc 32 is fitted over the shaft, it having a similar circular projection that fits into the other end of the core 30. The two discs and the core thus form a tape holding unit that is rotatable on the shaft. A rubber washer 34 is applied over the free end of the shaft to hold the discs and the core together. It is apparent that cores of different widths are accommodated for by varying space between the discs. Cores of different diameters require only the substitution of discs of different diameters.

The second coil of tape 25 is shown as wound onto the core 30. For illustrative purposes, this coil on the core 30 is shown as somewhat telescoped, a condition that is very undesirable and which is cured by rewinding in the present mechanism.

The tape 35 from the coil 25 is drawn down over the idler roll 21 between the tape 17 and the said idler roll. It then is superposed over the tape 17 as the same passes over the peeling drum 22 and down onto the rewind roll.

The peeling drum is mounted upon a shaft 40 supported within the vertical support 12. On its outer end, the peeling drum has a crank 41, by means of which it may be rotated. Obviously, a motor could be employed to drive this shaft. It will be seen that the surface of the peeling drum is serrated at 43, so that it presents only narrow edges in contact with the adhesive sur-

face of the tape. The back end of the shaft 40 receives a driving pulley 45 locked thereto by a set screw 46. The pulley has two grooves 47 and 48 of different depths. This provides a means to change the tension on a driving cable, as will appear.

The shaft 24 of the rewind core 23 is threaded at its outer end. An inner adapter disc 50 is threaded onto this end of the shaft 24 and has a projection 51 thereon adapted to enter one end of the opening in the core 23. The adapter 50 may be located axially along the shaft 24, so as to present the core 23 in proper alignment with the other cores. A similar adapter 52 is also threaded onto the shaft onto the opposite side of the spool 23. The latter adapter is turned sufficiently tightly to firmly clamp the core 23 onto the shaft 24 so that they rotate together.

The shaft 24 has a flange 53 engaging against the front face of the vertical support 12. The opposite end of the shaft 24 projects through the support 12 and is also threaded. It receives a friction clutch device, generally indicated at 56. In this friction clutch, there is a first fixed clutch member 57 threaded onto the shaft 24 and locked thereon by a lock nut 58. A driven disc 59 is also disposed rotatably on the shaft 24. A friction washer 60 is provided between the fixed disc 57 and the driven disc 59. On the other side of the driving disc 59 there is a locking disc 61, also threaded onto the shaft 24. A friction washer 62 is disposed between the driving disc 59 and the locking disc 61. The disc 61 is secured in set position by a lock screw 63.

The driving disc 59 is provided with a cable groove 64, by means of which it receives the cable 65 that extends between the driving disc 59 and the pulley 45 on the shaft 40.

It will be seen that the clutch friction may be varied by loosening the locking screw 63 and turning the locking disc 61 on the shaft 24 to clamp the driving disc 59 more tightly between the fixed disc 57.

It has also been discovered that the processing means 20 may apply a tension to the tape 17 that differs from the tape 35 drawn from the spool 23. This may be sufficient to produce enough inequality in the two laminations that they curl. It has also been discovered that this curling can be avoided by driving the processing means 20 from the main power means, through a slip friction 67 operated by the cable 65. The clutch 67 may be the same as the clutch 56.

Operation

The operation of the winding device is as follows:

A spool 13 of tape is disposed on the shaft 14. The tape 17 from this spool is then wound through the processing device 20, then under the idler roll 21, and over the peeling drum 22 with its adhesive side against the serrations 43. Thence, it is drawn down onto the spool 23. It adheres to the serrations 43 to an extent sufficient so that rotation of the drum 22 will unwind the tape from the spool 13, and draw it through the processing mechanism 20, where the latter is used. At the same time, the rotation of the crank 41 also rotates the rewind spool 23 but with a torque limited by the friction clutch 56. The clutch 67 is adjusted to apply sufficient friction to cause the rewind spool 23 to be rotated with only enough force to draw the tape off of the peeling drum 22.

The force through the clutch 56 is much less

than that required to withdraw the tape from its supply roll. It will be seen by reference to Fig. 1 that in this operation the tape does not usually extend directly down tangentially to both the peeling drum 22 and the rewind roll on the spool 23, as the force applied to the rewind roll is desirably limited to the smallest amount necessary to overcome the adhesion of the tape to the serrations 43 on the peeling drum.

It will also be seen that an even force is applied to the tape in the rewinding operation. Any small variations that would be occasioned in the force applied to the tape drawn by the rewind roll off of the peeling drum are insufficient to apply a tension to the tape being rewound that will materially vary between the start of the rewind roll and its finish at a substantially increased diameter. Further, the slip friction will inherently accommodate large variations in this tension to prevent it from increasing to a point where excess tension would be applied and resulting telescoping would occur.

Where it is desired to produce laminated tape, other rolls, such as the roll 25, may be included. This tape is then wound down under the idler roll 21, onto the top of the tape 17 with its adhesive tape against the tape 17. It adheres to this latter and is drawn over the peeling drum by the adhesiveness of the tape 17 to the serrations 43. In this arrangement, it is desirable to boost the delivery of the tape to the friction roll from the supply, to lower its tension to equal that of the tape drawn from the roll 25. This may be accomplished by driving the processing means 20 through the slip clutch 67.

This tape rewinding device is conveniently adapted to rerolling tape into smaller rolls, for rewinding laminated tape, for salvaging telescoped tape rolls, and for providing measured length of tape on rolls. As the amount of tape withdrawn from the supply roll 13 is a function of the number of turns of the peeling drum 22, it is readily understood that a certain number of rotations of the peeling drum will withdraw a certain amount of tape from the supply roll and rewind it onto the rewinding roll 23. Ordinarily, it is so easy to count the rotations of the crank 41 that it would not be necessary to supply a counter on the peeling drum. It may be remarked that, where the unwinding and rewinding force is applied to the rewinding roll, the constantly increasing diameter of this roll presents insurmountable difficulties in determining the amount of rewound tape as a function of the number of rotations of the power means.

It will, of course, be understood that the peeling drum or the processing means, or both, could be geared directly to the rewinding roll through a slip friction mechanism and that means other than the cable 65 could be used for this transmission of power. Other means of this character would be chains or friction belts. Also, a low torque or an adjustable torque motor, or an equivalent means, could be used if it insures only a mold tension on the tape at the roll 23.

What is claimed is:

1. In a rewinding machine for rewinding adhesive tape from a supply roll to a rewinding roll, a base, a supply roll support on the base, a rewinding roll support on the base, a peeling roll on the base disposed to receive the adhesive tape from the supply roll, means to rotate the peeling roll, said peeling roll being thereby adapted to withdraw the tape from the supply roll, and to hold the same adhesively but with less force than

the adhesive force of the tape on the supply roll, the rewinding roll support being adapted to hold a rewinding roll to receive the tape from the peeling roll, and low torque means to rotate the rewinding roll support, said peeling roll having a serrated surface for limited contact with the tape, the serrations being normal to the axis of rotation.

2. A device of the type described, comprising a support member; means for rotatably supporting a supply roll of tape on said support member; means for rotatably supporting a rewinding roll on said support member; a peeling drum rotatably mounted on said support member for pulling adhesive tape from a supply roll, the periphery of said peeling drum containing a series of serrations normal to the axes of rotation; means for rotating the peeling drum; and means interconnected with the peeling drum for rotating the rewinding roll support when the peeling drum is rotated so as to pull the tape off the peeling drum.

3. The method of rewinding pressure responsive adhesive tape from a supply roll onto a rewinding roll, which includes the steps of pulling the tape from the supply roll by a rotating peel-

ing drum having the tape in frictional adhesive contact with the peripheral surface thereof; and pulling the tape from the peeling drum onto the rewinding roll with just sufficient force to overcome the adhesion of the tape to the peeling drum, so as to peel it therefrom.
